UNITED STATES PATENT OFFICE.

KARL OTTO HÜTT, OF MALDEN, MASSACHUSETTS.

BLIND OPERATOR AND LOCK.

No. 802,167.

Specification of Letters Patent.

Patented Oct. 17, 1905.

Application filed June 10, 1903. Serial No. 160,789.

To all whom it may concern:

Be it known that I, KARL OTTO HÜTT, a citizen of the United States, residing in Malden, in the county of Middlesex and State of Massachusetts, have invented an Improvement in Blind Operators and Locks, of which the following description, in connection with the accompanying drawings, is a specification, like characters on the drawings representing like parts.

This invention relates to a window-blind operator and lock of that class in which the blind may be opened and shut from inside the room without opening the window.

The present invention has for its object to provide a simple and highly-efficient mechanism for the purpose specified.

The particular features of this invention will be pointed out in the claim at the end of this specification.

Figure 1 is an elevation showing the blinds in their closed position and looking from the outside of the house; Fig. 2, an elevation with the blinds closed and looking from within the room; Fig. 3, a detail in elevation and section, on an enlarged scale, of the operating mechanism to be referred to; and Figs. 4 and 5, details to be referred to.

Referring to Fig. 3, *a* represents a rod or arm which is engaged with the blind *b*, and, as shown, the said rod is extended through a staple *c*, attached to the under side of the blind. The rod *a* is secured to the end of an upright shaft *d*, extended through the window-sill *e* and provided below the same with a bevel-gear *f*, having a hub *g*, which rests on a washer or collar *h*, fast on a bent stud, post, or bracket *i*, attached to a plate *j*, which is screwed or otherwise fastened to the outside of the building *k*. The supporting bracket or post *i* is provided with an annular groove *m*, into which projects a screw *n*, carried by the hub of the gear *f*, whereby the bevel-gear is locked on the support *i* against longitudinal movement, yet is free to rotate thereon. The bracket or post *i* is provided with a laterally-extended lug or hollow boss *l*, which forms a bearing for a shaft *8*, extended through the base of the window substantially at right angles to the shaft *d*. The shaft *8* has secured on it, as by a screw *9*, a bevel-gear *10*, which meshes with and rotates the bevel-gear *f*. The shaft *8* within the house or building has a bearing in a rosette *12*, screwed or otherwise suitably secured to the building. The shaft *8* is extended through

and beyond the said rosette and is provided with a portion *13*, which is angular in cross-section and upon which is fitted the hub *14* of a handle *15*, having at its front end a recess or socket *16*, in which is located a helical spring *17*, which bears against the hub *14*, and a nut or disk *18*, which engages the threaded end *19* of said shaft. The hub *14* of the handle *15* is capable of movement longitudinally on the shaft, but is fitted onto the angular portion *13*, so as to cause the shaft to be rotated when the handle is turned. Provision is made for locking the handle from rotation under normal conditions, and for this purpose the rosette *12* is provided with one or more teeth or projections *20*, which coöperate with suitable recesses or notches *21* on the front face of the hub *14*. (See Figs. 4 and 5.) In the present instance the rosette is shown as provided with two teeth *20*, which are arranged substantially diametrically opposite, and the hub *14* is shown as provided with three sets or pairs of notches *21*, similarly arranged.

Under normal conditions the notches *21* engage the projections *20*, as represented in Fig. 3, and when in this position the shaft *8* is locked against rotation and the blind is held stationary, which may be in its closed or fully-opened position or in a partially-opened position. As shown in Figs. 1 and 2, the blinds are closed. Assume that it is desired to open the same. In this case the operator within the room pulls upon the handle *15* until the recesses or notches *21* are disengaged from the teeth or projections *20*, after which the handle is turned in the proper direction to open the blind, which is accomplished by the bevel-gear *10* rotating the bevel-gear *f* and its shaft *d*, the latter in its rotation carrying with it the crank or rod *a*, which is in engagement with the blind by the staple *c*. When the blind has been opened to the extent desired, the operator releases the handle, which is moved by the spring *17*, so as to again engage a pair of the notches *21* with the teeth or projections *20*, and thus lock the blind in the position into which it has been turned. The outward movement of the handle *15* may be limited, as herein shown, by a shoulder *25* on the interior thereof engaging the nut or disk *18*.

Provision is made for enabling the blind to be removed when desired, and for this purpose the crank rod or arm *a* is detachably fastened to the shaft *d*, which may be ac-

complished, as herein shown, by a pin 26, which is passed through a hole in the rear end of the crank or arm after the latter has been passed through a hole in the shaft *d*, as 5 clearly shown in Fig. 3, the crank or arm *a* having on it a collar or projection 27, which engages the shaft *d* on the side opposite to the pin.

The mechanism on the outside of the 10 house or building may be protected from the weather by a suitable cover 30, which may be screwed or otherwise secured to the building.

By the term "blind" I desire to be understood as including a shutter.

I claim—

The combination with a blind, of a crank arm or rod in engagement therewith, a vertically-arranged shaft to which said crank 20 arm or rod is secured, a bevel-gear fast on said shaft and provided with a hub, a bracket attached to the building and upon the upper end of which said hub is loosely fitted,

means carried by the said hub and engaging said bracket to prevent longitudinal movement of the hub on said bracket yet permit rotary movement of said hub thereon, a second shaft extended through the building and provided with a bevel-gear in mesh with the bevel-gear on the vertically arranged shaft, a handle on said second shaft provided with a recess, a rosette provided with a tooth or projection coöperating with the recess in said handle, and a spring within said handle to normally keep the recess in the handle in engagement with the tooth or projection on the rosette, substantially as described.

In testimony whereof I have signed my name to this specification in the presence of 40 two subscribing witnesses.

KARL OTTO HÜTT.

Correction in Letters Patent No. 802,167.

It is hereby certified that the name of the patentee in Letters Patent No. 802,167, granted October 17, 1905, for an improvement in "Blind Operators and Locks," was erroneously written and printed "Karl Otto Hütt," whereas the said name should have been written and printed *Karl Otto Hiitt*; and that the said Letters Patent should be read with this correction therein that the same may conform to the record of the case in the Patent Office.

Signed and sealed this 19th day of December, A. D., 1905.

complished, as herein shown, by a pin 26, which is passed through a hole in the rear end of the crank or arm after the latter has been passed through a hole in the shaft *d*, as 5 clearly shown in Fig. 3, the crank or arm *a* having on it a collar or projection 27, which engages the shaft *d* on the side opposite to the pin.

The mechanism on the outside of the 10 house or building may be protected from the weather by a suitable cover 30, which may be screwed or otherwise secured to the building.

By the term "blind" I desire to be understood as including a shutter.

I claim—

The combination with a blind, of a crank arm or rod in engagement therewith, a vertically-arranged shaft to which said crank 20 arm or rod is secured, a bevel-gear fast on said shaft and provided with a hub, a bracket attached to the building and upon the upper end of which said hub is loosely fitted,

means carried by the said hub and engaging said bracket to prevent longitudinal movement of the hub on said bracket yet permit rotary movement of said hub thereon, a second shaft extended through the building and provided with a bevel-gear in mesh with the bevel-gear on the vertically arranged shaft, a handle on said second shaft provided with a recess, a rosette provided with a tooth or projection coöperating with the recess in said handle, and a spring within said handle to normally keep the recess in the handle in engagement with the tooth or projection on the rosette, substantially as described.

In testimony whereof I have signed my name to this specification in the presence of 40 two subscribing witnesses.
